UNITED STATES PATENT OFFICE.

JOSEPH E. EARNEST, JR., OF REED CITY, MICHIGAN.

CHURN.

967,891.

Specification of Letters Patent. Patented Aug. 23, 1910.

Application filed May 19, 1910. Serial No. 562,231.

To all whom it may concern:

Be it known that I, JOSEPH E. EARNEST, Jr., a citizen of the United States of America, residing at Reed City, in the county of 5 Osceola and State of Michigan, have invented certain new and useful Improvements in Churns, of which the following is a specification, reference being had therein to the accompanying drawings.

10 This invention relates to improvements in churns and its object is to provide certain new and useful features in the construction and arrangement of parts all as hereinafter more fully described reference being had to 15 the accompanying drawings, in which—

Figure 1 is a perspective view of a device embodying the invention; Fig. 2 an enlarged vertical section of the same; Fig. 3 a plan view of Fig. 2 with parts broken away to 20 show the construction; and Fig. 4 a plan view with the cover removed.

As shown in the drawing 1 represents a suitable cylindrical receptacle or body preferably formed of sheet metal having a downwardly extending bottom flange 2 to receive a suitable base 3 which extends upward within the flange to support the bottom 4 of the receptacle. Secured to the base 3 are suitable legs 5 for supporting the churn at 25 the proper height from the floor. Near the upper end of the receptacle the same is provided with a hoop or ring 6 around the outer side thereof and the upper edge of the body is formed over the upper edge of 30 this ring to prevent the ring from coming off and to strengthen the upper edge of the body. This formed over edge above the ring 6 is provided with grooves 7 in opposite sides of the receptacle to receive the ends 35 of a cross strip 8 which is inserted therein by springing the upper edge of the receptacle and the strip. This strip is provided with holes to receive the upper ends of vertical shafts 9 of paddles for stirring and 40 churning the cream in the receptacle. Secured to these shafts are transverse strips 10 to the outer ends of which are secured blades 11 and the lower ends of the shafts 9 are reduced to engage sockets 12 in the bottom 45 4 of the receptacle. 13 is a suitable cover having a flange to engage the upper rim of the receptacle and this cover is detachably secured in place by rods 14 having hooked lower ends to engage beneath the ring 6 and screwthreaded at their upper ends to 50 receive thumb nuts 15, the rods passing

through slots 16 in opposite sides of the cover with the thumb nuts engaging the upper surface of the cover.

Bolted to the upper side of the cover are 60 two bearing brackets 17 for a transverse shaft 18 which is provided upon one end with a crank handle 19 for turning the same and secured upon this shaft inside the bearing brackets are two gears 20 adapted to engage pinions 21 detachably secured to the upper reduced ends 22 of the paddle shafts 9 which extend upward through openings in the cover. A transverse strip 23 extends across the cover between the bearing brackets 17 and the reduced upper ends of the paddle shafts extend upward through openings in this strip and are provided with a further reduced end forming a shoulder to engage the lower side of the pinions. Each 75 shaft is provided with a fixed transverse key 24 to engage a transverse slot in the pinion and thus detachably hold the pinion to turn with the shaft. The strip 23 and cover are also slotted for the passage of the keys 24 80 so that the shafts may be withdrawn from the cover or the cover lifted off.

A block 25 is pivotally attached by a bolt or screw 26 to the upper side of the strip 23 and this block is recessed at 27 at each end 85 to receive the pinions 21. These pinions are thus incased in the block and when the cover is removed and the shafts 9 thus disengaged from the pinions said pinions are held in place to be reengaged with the shafts 90 by said block. If it is desired to remove the pinions the block 25 may be turned on its pivot transversely of the strip 23 moving the pinions out of engagement with the gears 20 and from over the strip 23 where 95 they may drop downward out of the recesses in the block.

An opening is provided in the cover at one side of the strip 23 so that the operator may look into the churn and have access 100 thereto without removing the cover and this opening is closed by a suitable disk 28.

The parts are quickly and easily assembled by first placing the paddles within the churn body with their lower reduced ends 105 in engagement with the sockets 12. The transverse strip or bridge 8 is then slipped over the upper ends of the paddle shafts and sprung into the grooves to hold the upper ends of the shafts in proper position, 110 the cover with its assembled gearing is then placed upon the body and the reduced upper

end of the paddle shafts engaged thereby with the openings in the cover and their keys with the slots in the pinions which are held in proper position for such engagement by 5 the block 25. The cover is then made fast by the engagement of the hooks 19 with the ring 6 and the turning of the thumb nuts 15. Power may be applied to the shaft 18 to turn the gearing and actuate the paddles, 10 by the crank handle 19 or by means of a pulley 29 secured to the opposite end of the shaft.

Having thus fully described my invention what I claim is:—

- 15 1. The combination of a receptacle, vertically extending parallel paddle shafts in said receptacle, a cover to close the upper end of the receptacle a strip extending across said cover, said cover and strip having openings through which said shafts extend, pinions adapted to be detachably engaged by the upper ends of the paddle shafts when the cover is placed upon the receptacle, a block pivotally attached intermediate its 20 ends to the strip and provided with recesses at each end to receive the pinions and hold the same, said block being adapted to be turned on its pivot out of alinement with said strip to release said gears from said recesses, a shaft mounted in bearings on the 25 cover, gears on the shaft to engage the pinions, and means for turning the shaft.
- 30 2. The combination of a receptacle provided with grooves at each side near its upper end, a ring embracing the receptacle 35

adjacent to said grooves, a flange extending downward from the lower end of the receptacle, a base engaging the flange and extending upward within the same to support the bottom of the receptacle, legs secured to 40 the base, vertically extending parallel paddle shafts within the receptacle, a transverse strip engaging the grooves in the receptacle at its ends and provided with openings to receive the upper ends of the paddle shafts, 45 a cover for the receptacle provided with openings through which the paddle shafts extend and formed with notches in opposite sides, hooks engaging the ring on the receptacle and the notches in the cover, nuts on 50 the upper ends of the hooks to engage the cover, bearing brackets secured to the cover, a transverse shaft mounted in said bearing brackets, gears secured to said shaft, a transverse strip extending across the cover between the brackets and provided with openings through which the upper ends of the paddle shafts extend, pinions engaging the gears and adapted to be detachably engaged by the upper ends of the paddle shafts, and 55 a block pivotally attached to the said strip and recessed at each end to receive said pinions.

In testimony whereof I affix my signature in presence of two witnesses.

JOSEPH E. EARNEST, JR.
